UNITED STATES PATENT OFFICE

JAMES N. PAFF, OF PITMAN, NEW JERSEY

WATER-COOLED AIR AND STEAM NOZZLE FOR GAS GENERATORS

Application filed May 7, 1927. Serial No. 189,493.

My invention relates to new and useful improvements in a water cooled air and steam nozzle for gas generators, and has for its primary object to provide an exceedingly simple and effective device of this character which will be inexpensive in the cost of manufacture, but strong and durable and unlikely to break down under intense heat.

10 Another object of my invention is to provide a water-cooled nozzle for use in gas generators which will withstand the intense heat thus increasing the life thereof.

15 A further object of my invention is to construct a nozzle of this class from two different sized concentric shells providing an enclosed space for a cooling medium with tubes bridging said space for the passage of air and steam through the nozzle into the fire bed.

20 A still further object of my invention is to produce an air and steam nozzle capable of generating steam which may be afterwards used in the production of gas from coal in the usual manner.

25 Some of the advantages derived from the use of my improved nozzle are, low fuel consumption; increased capacity; longer operating period; reduction of the time required to clean the fire; better operating results; and a reduction in the oil requirements per thousand feet of gas generated.

30 With these and other ends in view, this invention consists in the details of construction and combination of elements herein-after set forth and then specifically designated by the claims.

35 In order that those skilled in the art to which this invention appertains, may understand how to make and use the same, I will describe its construction in detail, referring by numerals to the accompanying drawings forming a part of this application, in which:

40 Fig. 1, is a vertical sectional view of a conventional gas generator showing a nozzle constructed in accordance with my invention installed therein.

45 Fig. 2, is a section on the line 2—2 of Fig. 1.

Fig. 3, is an enlarged vertical sectional view of the nozzle per se.

Fig. 4, is a section of Fig. 3 on the line 4—4.

Fig. 5, is a bottom plan view of the nozzle.

Fig. 6, is a further enlarged fragmentary sectional view of the nozzle.

In carrying out my invention as herein embodied, 7 represents a conventional gas generator or furnace for the production of gas from coal, and includes the usual filling hopper 8, and the gas takeoff passageway 9. In the lower end of the furnace is mounted the usual grate 10 for supporting the firebed of coal during the generation of the gas, and below which is an air inlet 11.

On the grate 10, preferably centrally thereof, is mounted my improved water-cooled air and steam nozzle 12 comprising a pair of concentric casings 13 and 14, the latter being smaller than the former, so as to provide a space 15 for the cooling medium. These casings are braced or strengthened by stay bolts 16, or their equivalent.

The upper ends of both casings are closed, and may be of integral dome shape or other construction, while the space between said casings at their lower ends is closed by a cap ring 17 welded around its edges to the edges of both casings, the welding being indicated at 18. To the outer face of the cap ring 17 may be welded or otherwise attached a base ring 19 by means of which the nozzle may be fixed to the grate within the furnace or generator.

Bridging the space between the two casings are a pair of nozzle tubes 20, having their ends mounted in the walls of said casings, and open entirely therethrough for the passage of air and steam from the inside to the outside of the nozzle for projection into the fire bed surrounding the nozzle.

At some suitable location within the space 15 in the nozzle is arranged a water inlet 21, the upper end of which terminates a short distance below the top of the nozzle, and at some other suitable location within the space 15 is an outlet water leg 22 which runs substantially to the highest point of the nozzle. These water legs may be constructed of

channel iron sections having outturned flanges as shown in Fig. 4, so that they may be welded to the outer casing with their lower ends projecting through holes 23, one of which is shown, through the cap plate 17, the said holes being afterwards partially closed by welding to suitable fittings 24 therein, the welded material 25 filling in all the spaces occupied by the pipe fittings.

10 To the inlet water leg 21 is connected a water inlet pipe 26, while to the outlet water leg 22 is connected an outlet pipe 27, leading to a waste or a suitable accumulator for future use.

15 Beneath the grate and under the nozzle is located a steam spray device 28 connected by a pipe 29 or other suitable conduit with a source of steam supply, as a boiler or the aforementioned accumulator.

20 The furnace or gas generator having a bed of fire supported upon the grate around the nozzle, at certain periods steam is projected through the spray device into the space below the grate so that some of the

25 steam will pass into the nozzle and thence through the nozzle tubes 20 into the fire bed and also a portion of the steam will pass directly through the grate into the fire bed.

At other periods air will flow through the inlet 11 and pass into the fire bed through the grate and through the nozzle, the latter being for practical purposes, an extension of the grate surface, thus distributing the air and steam over the larger surface of the

30 fire bed, than is usual causing the coal to quickly break up and release its ingredients for mixture with the air and steam in the production of gas or other volatiles.

During these operations, the fire becomes 35 intensely hot, and the nozzle would soon disintegrate except for the body of cooling medium filling the space between the nozzle casings which has entered the inlet water leg, and a circulation of water is maintained by

40 letting the overflow run off through the outlet leg 22. Ofttimes, the water used as a cooling medium is turned to steam, so that when it flows out through the outlet water leg, it may be carried off to an accumulator 45 and projected into the fire bed through the spray device 28.

As suggested above, the construction of the nozzle is such as to practically increase the grate surface of the furnace or generator which is due to the fact that the steam and air pass into the fire bed throughout a

50 large proportion of the center of said fire bed, as well as through the bottom, producing a greater active surface resulting in quicker operations so that the costs are reduced.

Of course I do not wish to be limited to the exact details of construction as herein 55 shown as these may be varied within the

limits of the appended claims without departing from the spirit of my invention.

Having thus fully described my invention, what I claim as new and useful is:

1. A water cooled air and steam nozzle 70 comprising a pair of concentric different sized casings providing a water space between them, the upper ends of the casings being closed and the lower end of the space between said casings being closed, an inlet water leg within the space between the casings terminating below the upper end of the nozzle, an outlet water leg within the space between the casings with its upper end terminating at the highest point of the nozzle, 80 said water legs adapted to be connected with suitable inlet and outlet pipes to produce a circulation through the space between the casings, nozzle tubes bridging the space between the casings and having their ends mounted in said casings whereby steam and air may pass from the inner casing to the outside of the nozzle, and means to brace said casings.

2. The structure set forth in claim 4 90 wherein the water legs are formed of U-shaped sections and provided with outwardly projecting flanges by which they are fixed to a face of one of the casings within the space between said casings. 95

3. A water cooled air and steam nozzle comprising two casings closed at one end thereof, one smaller than the other and mounted within the larger one to provide a space for the reception of a cooling medium, 100 tubes mounted in said casings and providing communications between the interior of the inner casing and the exterior of the outer casing, means to close the space between the lower ends of the casings, means to convey 105 cooling medium to said space above the center thereof, and means to convey the cooling medium from said space at the extreme upper end thereof.

4. A water cooled air and steam nozzle 110 comprising two casings closed at one end thereof, one smaller than the other and mounted within the larger one to provide a space for the reception of a cooling medium, 115 tubes mounted in said casings and providing communications between the interior of the inner casing and the exterior of the outer casing, means to close the space between the lower ends of the casings, said means having holes therethrough, channel iron sections 120 mounted on the inner surface of the outer casing having their lower ends projecting through the openings in the bottom closure, and the upper end of one of said channel sections leading to the extreme upper end of 125 the outer casing while the upper end of the other channel section terminates short of the upper end of said outer casing, said channel sections forming water legs for the inflow and outlet of a cooling medium to 130

the space between the casings, and pipe fittings communicating with the lower ends of said water legs.

5. A water cooled air and steam nozzle comprising a double walled cylindrical body, providing a central chamber closed at one end and open at the other for the reception of the "blast," and a compartment surrounding the central chamber from the open end 10 of the latter to and over the closed end thereof to contain a cooling medium, means secured in the body walls and bridging the compartment and providing communications between the central chamber and the 15 exterior of the body, a pipe leading into said compartment and terminating adjacent the closed end of the body, and another pipe projecting into said compartment and terminating at the extreme part of the closed 20 end.

In testimony whereof I have hereunto affixed my signature.

JAMES N. PAFF.
